UNITED STATES PATENT OFFICE,

JACOB HEINRICH MISSONG, OF FRANKFORT-ON-THE-MAIN, GERMANY.

STEAM-ENGINE.

1,108,923.

Specification of Letters Patent.

Patented Sept. 1, 1914.

Application filed February 28, 1911. Serial No. 611,510.

To all whom it may concern:

Be it known that I, JACOB HEINRICH MISSONG, head engineer, a subject of the German Emperor, and resident of Frankfort-on-the-
5 Main, Germany, with the post-office address Oederweg No. 126¹, have invented new and useful Improvements in Steam-Engines, of which the following is a specification.

The object of my invention is the construction of a simple and effective steam engine having an action analogous to an engine of the compound type and refers more especially to the means, whereby a common steam cylinder fitted with a common piston 10 and piston rod may be so worked, that one side of the cylinder acts under high pressure steam from the boiler, whereas the expanded steam passes directly or through a receiver to the other side of the cylinder to act there 15 very much as in the low pressure cylinder of the well known compound engines. A part only of the steam expanded at the high pressure side of the cylinder is admitted to the low pressure side, whereas the rest of the 20 expanded steam is disposed of in various ways, which may be used separately or combined. One means to dispose of this remaining steam is to discharge it from the receiver for heating or for any other desired 25 purposes. Another means is to compress part of the expanded steam and force it backward into the live steam pipe to the boiler.

In the drawings Figures 1 and 2 are longitudinal sections, part elevation and largely diagrammatic of two arrangements of an engine cylinder and associated devices embodying my invention.

Referring to Fig. 1, *a* is the cylinder of 40 uniform diameter, *b* the piston also of uniform diameter throughout and preferably about half the length of the cylinder, *c* the high pressure side, and *d* the low pressure side. Valves *g* and *k'* being closed and 45 valve *e* opened, steam enters at *e*, is cut off when the piston has moved a suitable distance, then expands, and finally, at the end of the stroke, is discharged and passes, either partially or completely, through passage *f* and valve *g* (which is now opened) into the receiver *h* which envelops the cylinder *a*. Valves *e* and *g* are both provided with governors; in the arrangement shown a single 50 pressure governor *r* controls both these 55 valves but separate governors may be used if desired and the governor or governors

may be of any usual type. From the receiver *h*, pipe connection *k* is made to the heating or other arrangement *k'* for the utilization of steam. When the piston reaches the end of its stroke and steam passes into receiver *h*, as has just been described, valve *k'* which is controlled by a centrifugal governor *o* is opened so that steam from *h* passes through passage *f'* and valve *k'* to the low pressure side *d*. The steam pressures upon the two sides of the piston will then be substantially equal. After the piston has advanced a short distance valve *k'* closes and the steam charge on the low pressure side expands during the further advance of the piston thus lessening, by the amount of work done during such expansion, the work which the fly wheel must do in carrying the piston back to the starting point. Exhaust finally takes place through the valve *l*. An overflow valve *m* is kept constantly closed by the live steam pressure applied through passage *f*. When the valve *g* closes so early that the piston compresses the expanded steam on the high pressure side back to the initial live steam pressure before the cylinder end is reached, and this time of closure will be earlier or later according as less or more steam is 85 needed by the heating or other arrangement *k'*, this overflow valve *m* will open and the compressed steam flow back into the supply pipe through passage *f'*.

Fig. 2 represents the same arrangement as Fig. 1 except that the centrifugal governor *o'* is connected to control both high pressure and low pressure inlet while the pressure governor *r'* acts only upon the exhaust valve *g* of the high pressure side. The mode of operation is as just described for the arrangement of Fig. 1.

Now what I claim and desire to secure by Letters Patent is the following:

1. In a steam engine the combination with a cylinder provided with a uniform diameter piston and piston rod, of means to admit live steam to one cylinder side, means to admit the expanded steam to the other cylinder side, and means to discharge part of the steam expanded at the high pressure side, without entering the low pressure side.
2. In a steam engine the combination with a cylinder provided with a uniform diameter piston and piston rod, of means to admit live steam to one cylinder side, means to admit the expanded steam to the other

cylinder side, and means to discharge part of the steam expanded at the high pressure side into a conduit for heating or cooking purposes without entering the low pressure side.

3. In a steam engine the combination with a cylinder provided with a uniform diametered piston and piston rod, of means to admit live steam to one cylinder side, means to admit the expanded steam to the other cylinder side, and means to discharge part of the steam expanded at the high pressure side by recompressing part of the expanded steam at the high pressure side.
- 10 4. In a steam engine the combination with a cylinder provided with a uniform diametered piston and piston rod, of means to admit live steam to one cylinder side, means to admit the expanded steam to the other cylinder side, and means to discharge part of the steam expanded at the high pressure side by recompressing part of the expanded steam at the high pressure side and returning part of it into the live steam pipe.
- 15 5. In a steam engine the combination with a cylinder provided with a uniform diametered piston and piston rod, of means to admit live steam to one cylinder side, means to admit the expanded steam to the other cylinder side, and of means to discharge part of the steam expanded at the high pressure side into a conduit for heating or cooking and part by recompressing the expanded steam at the high pressure side.
- 20 6. In a steam engine the combination with a cylinder provided with a uniform diametered piston and piston rod, of means to admit live steam to one cylinder side, means to admit the expanded steam to the other cylinder side, and means to discharge part of the steam expanded at the high pressure side by recompressing the expanded steam and returning part of it into the live steam pipe, a receiver, an automatic pressure regulator acting on the admission valve for live steam, and of a centrifugal regulator acting upon the steam admission valve for the other end of the cylinder.
- 25 7. In a steam engine the combination with

a cylinder provided with a uniform diametered piston and piston rod, of a receiver, means to admit live steam to one cylinder side, means to admit the expanded steam to the other cylinder side, and means to discharge part of the steam expanded at the high pressure side from the receiver into steam utilization means and another part by recompressing the expanded steam at the high pressure side back into the steam supply.

8. In a steam engine the combination with a cylinder provided with a uniform diametered piston and piston rod, of means to admit live steam to one cylinder side, means to admit the expanded steam to the other cylinder side, means to discharge part of the steam expanded at the high pressure side by recompressing the expanded steam and returning part of it into the live steam pipe, a receiver, and an automatic regulator acting on the admission valve for live steam.

9. In a steam engine the combination with a cylinder provided with a uniform diametered piston and piston rod, of means to admit live steam to one cylinder side, means to admit the expanded steam to the other cylinder side, means to discharge part of the steam expanded at the high pressure side by recompressing the expanded steam and returning part of it into the live steam pipe, a receiver, an automatic pressure regulator acting on the admission valve for live steam, and of a centrifugal regulator acting upon the steam admission valve for the other end of the cylinder.

In testimony, that I claim the foregoing as my invention, I have signed my name in presence of two witnesses, this fifteenth day of February, 1911.

JACOB HEINRICH MISSONG.
